RECEPTACLE FOR DISCARDED RAZOR
BLADES

Karl Kneis, Los Angeles, Calif.

Application September 1, 1948, Serial No. 148,415

Term of patent 3½ years

(Cl. D4—3)

To all whom it may concern:

Be it known that I, Karl Kneis, a citizen of the United States, residing at Los Angeles, in the county of Los Angeles and State of California, have invented a new, original, and ornamental Design for Receptacle for Discarded Razor Blades, of which the following is a specification, reference being had to the accompanying drawing, forming a part thereof.

Fig. 1 is a front elevational view of the receptacle for discarded razor blades, showing my new design.

Fig. 2 is a side elevational view of the receptacle.

Fig. 3 is a rear elevational view of the receptacle.

Fig. 4 is a side elevational view of the receptacle but looking from the opposite side from that shown in Fig. 2.

Fig. 5 is a top plan view of the receptacle.

I claim:

The ornamental design for a receptacle for discarded razor blades, as shown.

KARL KNEIS.
